WELBY DINSMORE, OF PIEDMONT, CALIFORNIA

BILL FOR DECOYS

Application filed January 11, 1930. Serial No. 420,115.

The invention is for a bill for decoys and has special reference to a bill or beak for decoys of the duck variety.

The main object of the invention is to provide a resilient bill or beak for decoys of the wild fowl variety, which is unbreakable, and which may be utilized to replace broken bills or beaks on decoys.

Existing types of decoys are equipped with bills or beaks of material similar to the body material which is usually of a brittle nature, also some are equipped with bills or beaks of a different material than the body, though not flexible, thereby causing breakage of some co-operating part of the decoy.

The bill or beak, of small section, usually becomes broken when said bill or beak strikes a nonresilient surface, as when dropped accidentally or otherwise. A broken bill or beak makes a decoy practically worthless. The invention is adapted to prevent such damage to decoys, and, due also to low cost of manufacture, and ease of attachment, a particularly useful device is thereby provided.

Referring to the accompanying drawings, in which

Fig. 1 is a side elevation of the invention as attached to the head member of a decoy, shown dotted;

Fig. 2 is a longitudinal section of the invention;

Fig. 3 is a view of the contacting end; and

Fig. 4 is a transverse section taken on line 4—4 of Fig. 2.

Similar reference characters are used to designate similar parts throughout the several views.

Reference character 1 indicates the head of a decoy, said head member being provided with a protuberance 2 over which the recess 3 in the bill or beak 4 is fitted, the contacting surfaces between protuberance 2 and recess 3 being provided with a coating of cement for the purpose of firmly attaching the two members together. A thin edge 5 is provided so as to provide an unbroken contact surface at the exterior joint 6.

The bill or beak is preferably molded in one piece from soft rubber, though it may be manufactured by any known method of any

resilient material or resilient combination of materials.

The bill or beak is to be made of such shape as to approximate the form and contour of the specific type of decoy to which it is to be adapted.

The method of attaching the bill or beak to the head of the decoy is subject to variation; such variation, as is consistent with the specification and the appended claims, providing no departure from the spirit or scope of the invention or sacrificing any of the advantages thereof.

I claim:

1. A bill for a decoy for water fowl, composed of a resilient material formed to the approximate shape of the bill of said water fowl, and means for attaching said bill, in relative position to the head member of said decoy.

2. A bill for decoys for ducks composed of a resilient material formed to the approximate shape of the bill of a duck, a recess in said bill to receive a protuberance on said decoy, and means for retaining said bill on said protuberance in relative position to the bill of a duck.

In testimony whereof I have affixed my signature.

WELBY DINSMORE.
